NOZZLE CHANNEL CONSTRUCTION

Georg Schaper, Muelheim-Ruhr-Broich, Germany, assignor to Holzwarth Gas Turbine Co., San Francisco, Calif., a corporation of Delaware

Application April 20, 1935, Serial No. 17,467
In Germany April 23, 1934

8 Claims. (CL. 60—41)

The present invention relates to an improved construction of the nozzle or nozzles connected with the discharge end of the explosion chambers of explosion gas turbines, and particularly to 5 constructions in which a plurality of explosion chambers discharge into a common nozzle construction containing a single nozzle or a plurality of individual nozzles.

The construction and arrangement of the nozzle channel, that is, the passageway leading from the outlet or nozzle valve at the discharge end of an explosion chamber of an explosion turbine to the inlet end or ends of the nozzle or nozzles associated therewith, have caused considerable difficulties even when each explosion chamber is provided with its own individual multiple nozzle structure. For on the one hand the walls of the nozzle channel must withstand the shock and strain of very high sudden gas pressures upon 10 the interior thereof and also the more or less constant pressure of the cooling agent from the outside thereof, while on the other hand they are subjected to very great temperature stresses, the cooling agent pressure being in most cases made 15 very high in order to effect removal of heat at high temperature ranges and thus make possible an economical utilization of the abstracted heat; in addition, there exists the further requirement that the size of the nozzle channel be kept as 20 small as possible in order to reduce to the smallest possible degree the transfer of heat to the walls of such channel. These difficulties are aggravated when, according to more recent proposals, a plurality of explosion chambers are 25 made to operate upon a common nozzle or group of nozzles: for in such case not only is the size of the nozzle channel necessarily increased, so that a certain increased heat loss must be taken 30 into account with the simplification of the construction, but above all the heat transfer is increased because, the combustion chamber size and the cycle frequency remaining the same, the quantity of gases discharged into the nozzle channel per unit of time is multiplied correspondingly to the number of explosion chambers connected to the common nozzle channel. The known methods of building the nozzle channel 35 cannot adequately take care of the high temperature stresses which result under these new conditions, particularly with the wall thicknesses heretofore employed. If the stresses are to be reduced to a permissible magnitude by reducing the thickness of the walls (and in this connection the wall 40 thicknesses under present day conditions can be estimated at a maximum of 8 mm.), then the ar-

angement and construction of the nozzle channel as heretofore suggested must be abandoned if the nozzle channels are to withstand, with the reduced wall thicknesses, the very great gas pressure upon one side and the cooling agent pressure upon the other side. 5

It is accordingly an object of the invention to provide a nozzle channel construction for leading the hot, high pressure explosion gases of one or more constant volume explosion chambers to 10 a nozzle assembly, the nozzle channel being constructed to withstand high internal and external pressures while at the same time dangerous temperature stresses are avoided. It is also an object of the invention to provide a nozzle channel 15 construction wherein a nozzle channel built of relatively thin walls is elastically suspended within a jacket or casing of relatively thick walls in such a manner that the channel can expand and contract in correspondence with rise and fall of 20 the temperature of its walls, so that such walls can readily adapt themselves to the fluctuating temperatures and pressures to which they are subjected during the normal operation of an 25 explosion turbine.

In accordance with the present invention there is provided a construction for the nozzle channel and nozzle or nozzles of explosion chambers, such as are particularly suited for explosion turbines, in which a plurality of chambers discharge 30 into a common individual nozzle or common group of nozzles, such construction being characterized by the fact that the member which forms the nozzle channel lying between the nozzle valve and the nozzles is constructed in the form of an 35 elongated thin-walled tube and is surrounded by a cooling space. Such a tube is inherently pressure-proof; in addition the external cooling agent pressure can operate uniformly on all sides thereof and so equalizes itself, so that a sufficient 40 mechanical strength against buckling of the tubular body is attained even with small wall thicknesses because, in spite of the manifold increase 45 in the heat transfer, no dangerous temperature stresses occur since the temperature drop through the walls is reduced as the wall thickness is reduced.

Other objects of the invention will appear from the following description and the features of novelty are set forth in the appended claims. 50

The invention will be further described with the aid of the accompanying drawing which illustrates an embodiment of the invention by way of example. In said drawing:

Fig. 1 represents a longitudinal section through 55

a nozzle construction in accordance with the invention and is taken along the line I—I of Fig. 2, the view being developed in the plane of the drawing;

3 Fig. 2 shows a partial longitudinal section through the nozzle structure, according to line II—II of Fig. 1;

Figs. 3 and 4 show respectively cross sections along the lines III—III and IV—IV of Fig. 1;

10 Fig. 5 is a partial view in elevation of the inner tubular body, looking in the direction of the arrow a of Fig. 1;

Fig. 6 shows on an enlarged scale a detail of Fig. 3;

15 Fig. 7 is a cross sectional view on an enlarged scale through the end of the nozzle, and

Fig. 8 shows on an enlarged scale the construction of the elastic ring connections between the inner tubular body and the outer jacket member.

20 Referring to Fig. 3 the rotor of the combustion gas turbine is shown at 1, the nozzle structure in accordance with the invention being shown in transverse section. The rings of rotor blades are shown at 2 and 3, while the housing is indicated

25 at 4. As is well understood in the art, the nozzle structure is connected with the discharge end of an explosion chamber, the outlet or nozzle valve of such chamber being shown at 5 in Fig. 1, such valve being arranged to open into an enlargement

30 7 of a tubular member 6. In the closed position the valve engages a seat 5a. This tubular member may, in accordance with the invention, be made to provide the common nozzle channel for two explosion chambers whose nozzle valves are

35 received in the tulip-shaped enlargements 7 at the opposite ends of such member. As can be seen from Figs. 1 and 2 the shape of the tubular member 6 is so determined that on the one hand the mouths of the nozzles connected therewith (see

40 especially Fig. 2) lie upon the surface of a cylinder concentric with the rotor axis, while on the other hand the tulip-shaped enlargements 7 are displaced from a plane parallel to the turbine rotor plane, so that they lie outside of the rotor

45 housing 4.

The tubular member 6 carries connections 8 one behind the other in the longitudinal portion lying between the two enlargements 7, the ends of such connections lying in a plane 9, 9 which is parallel to the rotor plane 10, 10. These connections preserve the breaking strength of the tubular member 6 in spite of the slitting provided for the gas outlet, and may be cast integrally with the member 6, such connections acting to connect

50 the upper and lower portions of the member 6 (Figs. 3, 4, and 6). The inlet sections of the nozzles 12 are attached to the connections 8, for example by welding at the points 9a. The nozzles 12 with their inlet sections 11 are made of a single piece, but they may be composed in known

55 manner of a number of parts connected together, for example, by welding. In each case the nozzles are completely machined prior to welding to the connections 8, and in particular they are completely smoothed down on their interior gas-

60 swept surfaces.

As shown in Fig. 7, there are provided slit-like cut-outs 13 at the discharge end of each of the nozzles, such cut-outs forming channels for the 65 cooling agent after the assembly of all of the nozzles with the tubular member 6 and after the welding at the points 14 is completed, so that a cooling agent can penetrate to the ends of the walls defining the nozzle outlets during the operation of the turbine and thus cool such walls,

By virtue of their tubular shape the walls of the parts 6, 7, and 8 can be made very thin without loss of strength against internal and external super-pressures. The small wall thickness causes only a small temperature drop between the inner and outer wall surfaces, so that the temperature stresses remain within permissible limits.

The two-part member which surrounds the tubular member 6 and thereby forms a cooling chamber consists of an exterior portion 15 and 10 an inner portion 16; the two parts are connected together in a plane 17, 17 which runs parallel to the rotor plane 10, 10, for example by means of welded joints 18 after inserting and securing the parts 6, 7, 8, 11, and 12. The securing of the 15 parts 6, 7, 8, 11, and 12 within the member 15 of the cooling jacket is effected by way of the elastic rings 19, which are attached to the flanges 20 of the cooling jacket member 15 on the one hand, and at the ends of the enlargements 7 on 20 the other, for example by welding, as can be seen from Figs. 1 and 8. The united cooling jacket parts 15 and 16, as can be seen from Figs. 3 and 4, likewise form a tubular member which is capable of sufficient resistance to the mechanical 25 stresses resulting from the cooling agent pressure. The tubular form is interrupted only by the connections 8, which penetrate the cooling jacket part 16, or by the nozzle inlet sections 11. At this place the strength of the cooling jacket 30 against the inner pressure can however be increased by employing staybolts 21 whose threaded portions 22 are received in the nipples 23 of the part 16 of the cooling jacket. The part 16 is connected with the outlet ends of the nozzle 35 by means of a thin elastic wall 24 which is arched outwardly to increase its elasticity. This wall 24 is connected laterally with the nozzle ends and is also radially connected with the two end nozzles, as by the welded joints 25, as can 40 be seen from Figs. 1, 3, 4 and especially Fig. 6. The inner member composed of the tubular body 6, the enlargements 7, the connections 8, the nozzle inlet sections 11 and the nozzles 12 is thus held within the outer body 15, 16 on the one 45 hand by the elastic rings and on the other by the elastic walls 24. In consequence of this elastic suspension the whole inner body is free to expand relatively to the outer body, since during 50 the operation of the turbine it assumes much higher temperatures than the outer body.

The flanges 26 hold the jacket members 15, 16 rigidly against the turbine housing 4; while the flanges 20 of the jacket member 15 are attached to the housings of the nozzle valves 5.

The explosion chambers referred to hereinabove are of the constant volume type employed with explosion turbines and may be of any suitable construction.

It will be recognized that many departures can be made from the specific form of the invention illustrated without departing from the spirit of the invention or the scope of the appended claims.

I claim:

1. In a constant volume explosion turbine plant, the combination of a constant volume explosion chamber, a nozzle assembly for directing the gases generated in said chamber against a turbine rotor, a nozzle channel between the nozzle assembly and the outlet end of the explosion chamber, an outlet valve at the discharge end of the chamber controlling the communication between such chamber and the nozzle channel, the walls of said channel being relatively

thin and being provided with one or more lateral passageways leading into the nozzle assembly, a relatively thick walled jacket about said channel and spaced therefrom to provide a cooling chamber adapted to receive a current of cooling agent, the jacket being connected to said channel to seal the cooling chamber, and elastic connections between said channel and said jacket for elastically suspending the channel within the relatively rigid jacket for enabling the channel to expand and contract as the temperature of its walls and the pressure thereon vary.

2. In a constant volume explosion turbine plant, the combination of two constant volume explosion chambers, a common nozzle assembly for directing the gases generated in said chambers against a turbine rotor, a nozzle channel in advance of the nozzle assembly and lying between the outlet ends of said explosion chambers, outlet valves at the discharge ends of said chambers opening approximately endwise into said channel, the walls of said channel being relatively thin and being provided with one or more lateral passageways leading into the nozzle assembly, a relatively thick walled jacket about said channel and spaced therefrom to provide a cooling chamber adapted to receive a current of cooling agent, the jacket being connected to said channel to seal the cooling chamber, and elastic connections between the ends of said channel and the said jacket for elastically suspending the channel within the relatively rigid jacket for enabling the channel to expand and contract as the temperature of its walls and the pressure thereon vary.

3. The combination as set forth in claim 2, wherein the nozzle channel is in the form of a generally tubular member, the ends of said tubular member being enlarged to receive the heads of the outlet valves, and the nozzle assembly being attached to said tubular member between said enlargements.

4. The combination as set forth in claim 2, wherein the lateral passageways are formed by tubular extensions integral with the channel and terminating in approximately the same plane, said nozzle assembly being attached to said tubular extensions. 5

5. The combination as set forth in claim 2, wherein the jacket is composed of a section overlying the part of the channel remote from the nozzles, and two sections connected to the first 10 section and to the upper and lower edges of the discharge end of the nozzles.

6. The combination as set forth in claim 2, wherein the nozzles are formed by hollow walls whose interiors communicate with the cooling 15 space between the nozzle channel and jacket, and reinforcing members passing through the interior of such walls and connected to the jacket above and below such walls.

7. The combination as set forth in claim 2, 20 wherein the elastic connections between the nozzle channel and the jacket comprise elastic rings of U-shaped cross-section, the lines of connection with such rings being located adjacent to the seats of the outlet valves. 25

8. The combination with the outlet valves of a plurality of constant volume explosion chambers of an explosion turbine, and a nozzle assembly for directing the gases generated in said chambers against a turbine rotor, of a nozzle channel 30 leading from said valves to said nozzle assembly and comprising a thin-walled tubular member of substantially circular cross-section whose axis is arranged approximately parallel to the plane of the rotor, a jacket about said tubular member 35 and spaced therefrom to provide a cooling space about such member, said jacket being made of a plurality of parts and being for the greater part of tubular shape to conform to the shape of said tubular member, and elastic arched walls connecting the cooling jacket with the outlet ends 40 of the nozzle assembly. 40

GEORG SCHAPER.
